US0D1070473S

(12) **United States Design Patent** (10) Patent No.: **US D1,070,473 S**
(45) Date of Patent: ** Apr. 15, 2025

(54) **COOKING APPLIANCE**

(71) Applicant: **LG Electronics Inc.**, Seoul (KR)

(72) Inventors: **Jaehung Chun**, Seoul (KR); **Taeoh Kim**, Seoul (KR); **Jonghak Lee**, Seoul (KR); **Junghoon Lee**, Seoul (KR)

(73) Assignee: **LG ELECTRONICS INC.**, Seoul (KR)

(**) Term: **15 Years**

(21) Appl. No.: **35/519,001**

(22) Filed: **Nov. 17, 2022**

(80) **Hague Agreement Data**

Int. Filing Date: **Nov. 17, 2022**

Int. Reg. No.: **DM/225254**

Int. Reg. Date: **Nov. 17, 2022**

Int. Reg. Pub. Date: **Nov. 17, 2023**

(30) **Foreign Application Priority Data**

May 17, 2022 (KR) 30-2022-0019551

(51) **LOC (15) Cl.** **07-02**

(57)

CLAIM

The ornamental design for a cooking appliance as shown and described.

DESCRIPTION

- 1.1 : Perspective
- 1.2 : Front
- 1.3 : Back
- 1.4 : Left
- 1.5 : Right
- 1.6 : Top
- 1.7 : Bottom

(Continued)

The broken lines depict portions of the cooking appliance that form no part of the claimed design.

This design is for a cooking appliance that can stir-fry, roast, deep-fry, boil, wok-hei, etc.; through the transparent part of the top cover, the user can check the cooking status of the food at the inside pot.

1 Claim, 7 Drawing Sheets
